UNITED STATES PATENT OFFICE.

ISAAC GIDEON VAN NEST AND ANDREW JOSEPH KILLEEN, OF LOS ANGELES,
CALIFORNIA.

AUTOMATIC SMUDGE-KINDLER.

1,102,616.

Specification of Letters Patent.

Patented July 7, 1914.

Application filed May 29, 1913. Serial No. 770,805.

To all whom it may concern:

Be it known that we, ISAAC GIDEON VAN NEST and ANDREW JOSEPH KILLEEN, citizens of the United States, residing at Los Angeles, in the county of Los Angeles and State of California, have invented certain new and useful Improvements in Automatic Smudge-Kindlers; and we do hereby declare the following to be a full, clear, and 10 exact description of the same, reference being had to the accompanying drawings, forming part of this specification, and to the figures and letters of reference marked thereon.

15 This invention relates to devices for lighting smudges or fires for preventing injury to vegetation, orchard trees, vines, etc., by the formation of frost when the temperature drops to or near the frost point.

20 The object of the invention is to provide a simple and convenient device which will be inexpensive to manufacture and distribute and which will be automatic in its action, the control being effected through 25 the differential expansion and contraction of the control parts due to changes in the temperature of the surrounding air.

The invention consists in certain novel 30 arrangements of parts, all as will be now described and pointed out particularly in the appended claims.

In the accompanying drawings,—Figure 1 is a perspective view of a preferred form 35 of the device embodying the present improvements. Fig. 2 is a detail elevation with the parts in operated or released position such as would be effected by a drop in temperature liable to cause dangerous conditions of the atmosphere.

40 Like letters of reference indicate the same parts in both figures of the drawings.

Inasmuch as the device is intended for use under rough and adverse conditions 45 which subject it to wide variations in temperature as well as moisture conditions of the atmosphere, it is preferably made entirely of metal, and as a convenient and preferred construction the main frame is composed of a metal strip of suitable cross section and weight, bent into a substantially

U-shape, forming a base A and side pieces or uprights B, B'. The uprights B, B' are rigidly connected to resist distortion by connecting members preferably in the form 55 of diagonal braces B² riveted firmly to the uprights B, B', and usually of metal strips which correspond in cross section and weight to the uprights. The frame thus formed is adapted to be held in vertical position by a 60 foot or cross piece which may be a simple strip C, pivotally connected at its center to the base A thereby adapting it to be turned at an angle to the base so as to extend on opposite sides thereof when the 65 frame is to be held upright, or to be turned substantially parallel with the base when the device is to be folded for storage or transportation. The whole frame is preferably of metal having a low-co-efficient of 70 expansion, such, for example, as iron or steel.

The uprights B, B' are adapted to support a cross lever D which for simplicity of construction may be a thin metal strip suitably guided at its ends in vertical slots or kerfs d, d, formed in the upper ends of the uprights, and the bottom of one of said slots or kerfs conveniently form the pivot or fulcrum for the lever. As thus constructed the 75 lever projects at its ends beyond the uprights and has one very long arm and one very short arm extending on opposite sides of the pivot or fulcrum. To the short arm of the lever there is pivotally connected the 80 upper end of a long rod E formed of a metal having a high co-efficient of expansion, such as for example, as brass, the lower end of said rod being adjustably connected with the lower portion of the upright. This rod E 85 is conveniently guided at its upper ends in a suitable bearing in a bracket e and at its lower end is threaded and passed through an opening in a bracket e' with adjusting nuts e² above and below the bracket whereby an 90 accurate adjustment of the rod may be effected and the rod locked securely in its adjusted position. The rod E extends parallel with the uprights B' and is effectually protected thereby so that it is not liable to 100 be bent or distorted in the rough usage to which devices of this kind are subjected.

On the upright B and near the upper end thereof there is pivotally mounted a gravitating igniter receptacle F adapted to be held in inoperative position by the long 5 end of the lever before referred to and should the temperature drop to a point where the contraction of the rod E raises the long end of the lever the igniter receptacle will be released, and dropping by gravity will discharge its contents on to the smudge material for igniting the latter, it being understood that the smudge material to be ignited is held in a suitable receptacle 10 or located on the ground at the side of the frame and in position to receive the contents of the receptacle. In the preferred construction the igniter receptacle F is mounted on a swinging arm or carrier G pivotally connected with the upright B at the 15 lower end and at its upper end adapted to engage a notch or tooth g on the under edge of the long arm of the lever, the position of the axis of the carrier being such that its weight and the weight of the receptacle F 20 normally tend to turn the same down to the position indicated in Fig. 2, and discharge the igniter material. To protect the contents of the receptacle from rain, dust, etc., it is preferably provided with a swinging 25 cover f normally occupying an inclined position as shown in Fig. 1, but adapted to swing out to the position shown in Fig. 2 when the receptacle is dropped to discharge 30 its contents whereby the free discharge of the contents of the receptacle is assured. 35

In making use of the device the receptacle F is filled with a chemical igniter composition which when discharged upon the smudge material or material to be ignited 40 will cause the automatic or spontaneous combustion of said material, and the device is set in such relation to the smudge material that the receptacle will discharge its contents into contact therewith. The thermostatic rod E is adjusted to effect the 45 release of the receptacle when the temperature drops to the degree where danger conditions prevail, and the receptacle is adjusted in its upright position in engagement with the long arm of the lever. The device is 50 left under these conditions of adjustments and should the temperature drop to the danger point, the contraction of the thermostatic bar releases the receptacle thereby discharging its contents and automatically inaugurateing a combustion of the material 55 provided for the protection of the orchard or vineyard in which the device is located.

The whole device, it will be noted, is of 60 exceedingly simple construction, cheap to manufacture, and may be stored and transported in a compact and convenient form.

What we claim is,—

1. A device of the character described 65 embodying a self-supporting frame having

uprights, a movable igniter carrier mounted on one of said uprights, a retaining lever for holding said igniter carrier normally in inoperative position, and a thermostatic bar pivotally connected with said lever and 70 extending parallel with the other upright.

2. A device of the character described embodying a vertically arranged frame, an igniter carrier pivotally mounted on said frame, a lever for retaining said igniter carrier normally in inoperative position, and a thermostat for moving said lever to 75 release the igniter carrier when the temperature drops to a predetermined degree.

3. A device of the character described 80 embodying a vertically arranged frame, an igniter carrier pivotally mounted on the upper portion of said frame, a lever extending transversely of and pivotally mounted on the frame and coöperating with the carrier to hold the same in inoperative position, and a thermostatic bar connected with said lever at its upper end and adjustably connected with the frame at its lower end 85 for moving said lever to release the carrier 90 when the temperature drops to a predetermined degree.

4. In a device such as described, the combination with the frame embodying the uprights and base piece, a transversely extending foot piece pivotally mounted on the base piece, and braces rigidly connecting the uprights, of a lever pivotally mounted on one upright and guided by the other to swing vertically, a thermostatic bar connected with one end of said lever and adjustably connected with one upright, an igniter carrier pivotally mounted on the other upright and coöperating with the lever whereby it is retained in inoperative 100 position, the arrangement being such that the lever is moved to release said igniter carrier by the contraction of the thermostatic bar due to a drop in temperature. 105

5. In a device such as described, the combination with the frame embodying uprights and base piece, a transversely extending foot pivotally connected with the base piece whereby it may be folded into substantial parallelism therewith, a brace rigidly connecting the uprights, an igniter carrier pivotally mounted on one of said uprights to swing downwardly by gravity, and a lever extending transversely between the uprights and coöperating with the igniter carrier to 115 hold the same in inoperative position, of a thermostatic bar pivotally connected with one end of the lever, a bracket in which said thermostatic bar is mounted, and an adjustable connection between the lower end 120 of the thermostatic bar and frame, substantially as described.

6. In a device such as described, the combination with the vertical frame embodying uprights slotted at their upper ends, a lever 130

pivottally mounted in one of said slots and guided to move vertically in the other of said slots, and a thermostat for moving said lever on its axis, of an igniter carrier pivotally mounted on one of said uprights and coöperating with the lever whereby it is held in inoperative position, a receptacle for the ignition material mounted on said

carrier, and a gravitating cover for said receptacle.

ISAAC GIDEON VAN NEST.
ANDREW JOSEPH KILLEEN.
